UNITED STATES PATENT OFFICE.

CHARLES H. RICHARDS, OF CHICAGO, ILLINOIS, ASSIGNOR TO LOUIS ARMSTRONG, OF CHICAGO, ILLINOIS.

GRINDING-DISK.

No. 927,077.

Specification of Letters Patent.

Patented July 6, 1909.

Application filed May 18, 1907. Serial No. 374,360.

To all whom it may concern:

Be it known that I, CHARLES H. RICHARDS, a citizen of the United States, and a resident of Chicago, in the county of Cook and State of Illinois, have invented certain new and useful Improvements in Grinding-Disks; and I do hereby declare that the following is a full, clear, and exact description thereof, reference being had to the accompanying drawings, and to the letters of reference marked thereon, which form a part of this specification.

This invention relates to improvements in millstone-dresses and more especially to the construction in the working faces of a pair of plates or disks adapted for treating particles of cooked or partially cooked corn or other cereal to first flatten and thereafter roll the particles into individual finished form.

20 My invention consists in the matters hereinafter set forth and more particularly pointed out in the appended claims.

In the drawings:—Figures 1 and 2 are plan views of the working faces of the two grinding plates or bur wheels. Figs. 3 and 4 are enlarged detail plan views of portions of the two plates shown in Figs. 1 and 2, respectively. Fig. 5 is a section taken on lines 5—5 of Figs. 1 and 2 showing the two plates arranged in operative relation to each other. Fig. 6 is a section taken on the lines 6—6 of Figs. 3 and 4 showing the two plates arranged in operative relation to each other. Fig. 7 is a section on the line 7—7 of Fig. 4. Fig. 8 is a section on the line 8—8 of Fig. 3.

As shown in said drawings, A and A¹ indicate the grinding plates or disks which are of the well-known annular form and will usually be arranged in vertical planes, with their working faces toward each other and separated about a thirty-second of an inch. Either or both of said disks may be turned or driven in such manner as to afford relative rotative movement between them. Preferably the grinding disks are rotated in opposite directions in order that the relative movement between their faces may be large without the necessity of rotating either plate at a greater speed than is convenient. The working faces of the disks are of like construction with the exception of a slight difference in the arrangement of the furrows in their working faces, as will hereinafter be

explained. Each of said disks has the usual eye a and is provided on its inner face with a central concave part or recess A² concentric with the eye, into which is fed the material to be acted upon, and outside of said recess with an annular marginal grinding surface which is generally flat, and parallel with the corresponding surface of the other disk, and on which are formed feeding and grinding channels or furrows and intervening lands or ridges. The said recesses A² are made of considerable depth and occupy a substantial part of the central part of the disk.

Each of the disks is provided on its marginal working portion with alternate broad lands B and relatively narrower grooves or furrows C C¹. The said furrows are arranged to extend from the inner to the outer margin of the annular working surface, and are inclined with respect to radial lines of the disks. The outer parts of the furrows are inclined with respect to the main parts thereof and are disposed at smaller angles with the radial lines of the disks, the purpose of such change in direction of the furrows being to lessen at the outer parts of the disks the rate of outward feed or travel of the material being acted upon. The faces of the lands B B are flat and in planes perpendicular to the axis of rotation of the disks. The lands and furrows occupy that annular portion of the disk which, in grinding disks, have heretofore been known as the skirt of the disk.

Each of the furrows C C¹ is formed with a shoulder c at one side thereof, said shoulder being perpendicular to the flat faces of the lands B B, and an inclined bottom surface c¹ which extends from the plane of the land and meets the bottom or inner edge of the said shoulder c. The two disks are rotated, as shown by the arrows on Figs. 3 and 4, in a direction to carry the shoulders c of the furrows C in advance of the inclined surfaces c¹ thereof.

The two disks A A¹ are also provided with a series of auxiliary recesses or furrows, located adjacent to and extending outwardly from the central recesses of said disks and of which those in the disk A are indicated by D D and those in the disk A¹ are indicated by D¹ D¹. One of the said furrows D or D¹ is located at the inner end of each of

the main furrows C C¹. The auxiliary furrows extend diagonally across the inner ends of the main furrows. Said furrows or recesses D D¹ are, moreover, provided with 5 bottom surfaces which are inclined in the same direction as the bottom surfaces of the main furrows C C¹, but which are at a greater inclination to the flat surfaces of the lands than the said furrows C C¹; said furrows D 10 D¹, because of the greater inclination of their bottom surfaces, being of greater depth at their deepest parts than said main furrows C C¹.

Between the central recesses of the disks 15 A A¹ and the outer annular working faces thereof, are formed abrupt annular surfaces or shoulders E E¹, as shown in Figs. 6, 7 and 8, and the said auxiliary furrows D D¹ open into the said central recesses between said 20 shoulders E E¹. Said auxiliary furrows D D¹ form openings or spaces through which the material to be treated or acted upon by the disks passes from said central recesses to and between the working faces of said 25 disks. The furrows D D¹ in the two disks are generally alike, but as preferably constructed, differ somewhat from each other in the two disks, as will appear from the following:

30 Each of the furrows D is made by cutting perpendicularly into the face of the disk A along a line d, which is tangent to a circle of slightly less radius than the inner circumference or shoulder E at the inner edge of the 35 working face of the disk, and by forming an oblique flat face d¹ extending from a line d² which coincides with the shallower edge of the furrow C, until it meets the lower edge of the shoulder formed along the line d. 40 Said shoulder, indicated by the line d, extends across the inner end of the furrow C and terminates at the annular surface or shoulder E and is, by reason of the inclination of the bottom face of the groove, of tapered form; being deepest at the line of its 45 intersection with the surface E and extending to a point at its outer end, where it meets the line d².

Each furrow D¹ in the disk A¹ is made by 50 cutting perpendicularly into the face of said disk along a line d³ tangent to the inner circumference or shoulder E¹ at the inner margin of the working face of the disk and extending at an angle across the inner end of 55 the furrow C¹ into the face of the adjacent land B, and by forming an oblique surface d⁴ constituting the bottom of said furrow, which surface extends from a line d⁵ parallel with the abrupt shoulder of the next adjacent furrow C¹ and extending to the lower 60 edge or margin of said shoulder d³. Said shoulder d³ is of tapered form and of greatest depth where it meets the annular shoulder E¹. By this construction of the furrow D¹ a 65 narrow land portion d⁶ forming an extension

of the land B on the disk A¹, is formed between the trailing edge of said furrow and the leading edge of said furrow C¹.

By inspection of Fig. 6 it will be seen that the construction described in the inner or auxiliary furrows D D¹, provides along the annular shoulders E E¹ at the inner margins of the working faces of the disks, a series of spaces of considerable width into which the particles of the material being operated upon 70 may enter in the passage of said particles from the central recesses into the space between the working faces of the disks. It will be furthermore noted that the flat lands are 75 relatively wider than the furrows and that 80 they extend from points closely adjacent to the central recesses A² to the margins of the disks and are of increasing width from their inner to their outer ends.

The operation of the grinding disks is as 85 follows: The material operated upon will usually be cracked and cooked corn or hominy and the same will be fed in a moist condition into the central recess between the two disks. The operation will be the same, 90 however, when the material consists of other cereals, cooked or uncooked. The material is fed through the eyes a to the central space between the disks formed beneath the bottoms of the recesses A² and is thrown outwardly by centrifugal force and the particles thereof first enter the spaces formed by and between the inner or auxiliary furrows D D¹ which, in the deeper portions thereof, afford spaces wide enough to receive the largest of 95 said particles. As the particles of material pass outwardly along the inclined bottom surfaces of said auxiliary furrows D D¹, they are caught between the inclined bottom surfaces of the opposed furrows and are carried 100 between the adjacent surfaces of the lands between said auxiliary furrows, whereby each particle is squeezed or compressed to form a flat flake. The flat flakes thus formed, in their outward radial movement, 105 are carried into the main furrows C C¹ and being caught between the inclined bottom surfaces of opposed furrows and between the opposed lands are squeezed, kneaded and 110 rolled in such manner that they become 115 spongy or porous in texture and assume the form of small, elongated flaky cylinders. These cylinders are carried outwardly between the adjacent land surfaces until all 120 moisture has been excluded or driven off, and the material is discharged at the outer margins of the disks in a dry state. The change in the direction of the main furrows C C¹ has the effect of retarding the outward 125 progress of the particles of material so that they will remain a sufficiently long time under the action of the lands to insure the drying thereof before they are discharged from between the disks.

The particles of cereal being treated, after 130

being flattened, may cross one or more furrows and lands in their outward passage to the margins of the disks, during which time they are being rolled and dried. Inasmuch, 5 however, as the abrupt shoulders *c* of the furrows are carried, in the rotation of the disks, in advance of the inclined surfaces *c'* thereof, the crossing of said furrows by said rolled particles has no tendency to break up 10 or disintegrate the latter, because while occupying said furrows they are acted upon only by the opposing inclined surfaces or bottoms of said furrows which carry said rolled particles under moderate pressure 15 gradually to the planes of the lands. Moreover, the widening of the lands at their outer ends has the effect to subject the particles to a maximum rolling action, by which the rolled particles are dried.

20 I claim as my invention:—

1. A disk for the purpose set forth provided with a central eye and one side thereof with a wide recess surrounding the eye and outside of said recess with an annular or skirt portion, alternate lands and main furrows extending across said annular or skirt portion from points adjacent to said central recess to the periphery of the disk, said lands being made wide and increasing in width toward 25 their outer ends, and auxiliary furrows extending diagonally across the inner ends of the main furrows and opening into the said central recess, the leading edges of the main and auxiliary furrows being formed with 30 abrupt shoulders and the bottoms of said furrows being inclined toward their trailing edges where they meet the leading edges of the lands.

2. A disk for the purpose set forth provided with a central eye and one side thereof with a wide recess surrounding the eye and outside of said recess with an annular or skirt portion, alternate lands and main furrows extending across said annular or skirt portion from points adjacent to said central recess to the periphery of the disk, said lands being made wide and increasing in width toward 45 their outer ends, the leading edges of said main furrows being formed with abrupt shoulders and the bottoms of said furrows being inclined toward their trailing edges where they meet the leading edges of the lands, and auxiliary furrows extending diagonally across the inner ends of said main furrows, the leading edges of said auxiliary furrows being also shouldered and extending a distance diagonally across the inner 50 ends of the trailing edges of said lands, the bottoms of said auxiliary furrows being likewise inclined toward their trailing edges where they meet the leading edges of the lands and said auxiliary furrows being open throughout their width to said recess.

3. A disk for the purpose set forth provided with a central eye and one side thereof

with a wide recess surrounding the eye and outside of said recess with an annular or skirt portion, alternate lands and main furrows extending across said annular or skirt portion from points adjacent to said central recess to the periphery of the disk, and auxiliary furrows extending diagonally across the inner ends of the main furrows and opening into the said central recess, the leading edges of the main and auxiliary furrows being formed with abrupt shoulders and the bottoms of said furrows being inclined toward their trailing edges where they meet the leading edges of the lands, said main furrows being made of substantially uniform 70 width throughout their length and deflected at their outer ends to retard the feed of the material and the lands being made of increasing width toward their outer ends.

4. A pair of disks for the purpose set forth 85

arranged in parallel planes with their working faces adjacent to each other and separated a small distance, said disks being provided with central eyes and formed on their adjacent or working faces with central recesses surrounding said eyes and outside said recesses with annular or skirt portions, alternate lands and main furrows extending across said annular or skirt portions from points adjacent to said central recesses to 90 the peripheries of the disks, and auxiliary furrows extending diagonally across the inner ends of the main furrows, one edge of each of the main and auxiliary furrows being formed with an abrupt shoulder and the bottoms of said furrows being inclined toward their other edges where they meet the planes of the lands, said disks being designed to be 95 so relatively rotated that the shouldered edge of each of the main and auxiliary furrows of one disk is carried in advance of the inclined bottom thereof and approaches the shoulders of the furrows of the other disk from the land sides of said shoulders.

5. A pair of disks for the purpose set forth 100

arranged in parallel planes with their working faces adjacent to each other and separated a small distance, said disks being provided with central eyes and formed on their adjacent or working faces with central recesses surrounding said eyes and outside said recesses with annular or skirt portions, alternate lands and main furrows extending across said annular or skirt portions from points adjacent to said central recesses to 105 the peripheries of the disks, and auxiliary furrows extending diagonally across the inner ends of the main furrows, one edge of each of the main and auxiliary furrows being formed with an abrupt shoulder and the bottoms of said furrows being inclined toward their other edges where they meet the planes of the lands, said disks being designed to be 110 so relatively rotated that the shouldered edge of each of the main and auxiliary fur-

115

120

125

130

rows of one disk is carried in advance of the inclined bottom thereof and approaches the shoulders of the furrows of the other disk from the land sides of said shoulders, the 5 trailing ends of the auxiliary furrows of one of said disks extending a substantial distance into the inner ends of said lands.

In testimony, that I claim the foregoing as

my invention I affix my signature in the presence of two witnesses, this 14th day of May 10 A. D. 1907.
